UNITED STATES PATENT OFFICE.

LEWIS C. PACKER, OF SPRINGFIELD, MASSACHUSETTS, ASSIGNOR TO WESTINGHOUSE ELECTRIC & MANUFACTURING COMPANY, A CORPORATION OF PENNSYLVANIA.

MOUNTING FOR SEWING-MACHINE MOTORS.

Application filed February 19, 1921. Serial No. 446,406.

To all whom it may concern:

Be it known that I, LEWIS C. PACKER, a citizen of the United States, and a resident of Springfield, in the county of Hampden 5 and State of Massachusetts, have invented a new and useful Improvement in Mountings for Sewing-Machine Motors, of which the following is a specification.

My invention relates to machines, such as 10 sewing machines, that are equipped for operation by electric motors, and it has for its object to provide a structure wherein the machine and the motor are united in an improved manner to form a strong, compact 15 and inexpensive combination.

My invention comprises a structure for mounting whereby an electric motor may be mounted upon the head of a sewing machine by means of a stub shaft.

Heretofore, it has been customary to drive 20 a sewing machine by means of a motor so disposed on a machine table as to engage the hand wheel, or by fastening the motor to the machine frame by means of a complicated and expensive supporting structure.

Briefly, my invention comprises providing the motor with an extra casing through 25 which a stub shaft projects into the head of the machine, and providing a resilient member so disposed within the extra casing as to bias said motor to a position in which a motor-driven pinion engages the hand wheel of the machine.

In the accompanying drawings,

Figure 1 is a side elevational view of a 30 portion of a sewing machine provided with a motor constructed in accordance with my invention.

Fig. 2 is a cross-sectional view of the 35 structure illustrated in Fig. 1, taken along the line II--II, thereof.

Fig. 3 is also a cross-sectional view of the 40 structure illustrated in Fig. 1, the section being taken along the line III--III thereof.

In the drawings, a sewing machine head 1 45 is provided with the usual shaft 2 and hand wheel 3. The head 1 is provided with an indented intermediate portion 4, as best shown in Fig. 2, the central portion of 50 which is provided with a boss 6 having a machined surface. The boss 6 is provided with a central threaded opening 5. Within the opening 5 is disposed a stub shaft 7, one end 55 of which is threaded to co-operate with

the threaded opening 5. Upon the opposite 60 end 9 of the shaft 7 is pivotally mounted an electric motor 10 provided with a shaft 11 upon which is mounted a driving pinion 12 which engages and drives the hand wheel 3 of the sewing machine.

The electric motor 10 is provided with an outer casing 13, one side of which is provided with an opening 14. This opening is closed by means of an auxiliary casing member 15 which extends thereover and is rigidly fastened to the motor casing 13. The casing 15 is provided with an opening 16 therein through which the shaft 7 extends. That portion of the casing 15 immediately adjacent to the opening 16 is machined flat so 70 as to engage the machined surface 6 of the head 1.

Upon the end 9 of the shaft 7 is mounted a coiled spring 17, one end of which is attached to the shaft 9 and the other end of 75 which is attached to the casing member 15. The spring tends to cause relative rotation between the pin 7 and the motor 10 in such direction as to maintain the pinion 12 in engagement with the hand wheel 3.

Thus the spring 17 and one end 9 of the shaft 7 are totally enclosed by means of the auxiliary casing member 15, while the other end of the shaft projects into threaded engagement with 85 the opening 5 in the head 1, thereby supporting the motor. Thus, it is seen that when the motor is in its operative position, the stub shaft 7 is rigidly fixed with respect to the head 1 and that the motor 10 is pivotally mounted thereon.

The shaft 7 is so disposed with respect to the motor 13 that the axis thereof passes substantially through the center of gravity thereof. By so mounting the motor, the 95 work imposed on the spring 17, that of maintaining the pinion 12 in yielding engagement with the hand wheel 3, is reduced to a minimum.

From the foregoing description, it will 100 be apparent that the only connection between the head 1 and the motor 10 is the stub shaft 7, and that all movable parts connected with the motor-mounting device are totally enclosed.

A device constructed in accordance with my invention may be assembled by mounting the stub shaft 7 within the auxiliary cas-

ing member 15. The casing member 15 is then attached to the motor casing 13 to close the opening 14 therein. The hand wheel 3 is then removed, and, by rotating the motor 10, the end 8 of the shaft 7 is moved into threaded engagement with the walls of the opening 5 in the head of the machine, thus locking the motor 10 in position. The motor is then biased to depress the driving wheel 12 below its normal position while the hand wheel 3 is mounted on the shaft 2. The motor is then released and is returned to its normal position, with the pinion 12 in engagement with the hand wheel 3 by means of the spring 17.

By reason of mounting the motor within the indented portion 4 in the head member 1, and by using a flat sided motor, the overall width of the machine is reduced to a minimum, thus permitting the use of a motor of this type on a machine of the drop-head type, in which a relatively wide machine could not be used with the standard type of table now in use.

While I have shown and described in detail but a single application of my invention, it will be obvious to those skilled in the art that it is not so limited but is susceptible of various minor changes and modifications without departing from the spirit thereof, and I desire, therefore, that only such limitations shall be placed thereupon as are imposed by the prior art or as are specifically set forth in the appended claims.

I claim as my invention:

1. In combination, a sewing-machine head comprising an upright standard having a hand wheel mounted thereon, a driving motor provided with a driving wheel yieldingly maintained in engagement with said hand wheel and means for mounting said motor on said upright standard, said means comprising a stub shaft projecting into said head, and said motor being pivotally mounted to move about said shaft as an axis.

2. In combination, a sewing-machine head comprising an upright standard having a hand wheel mounted thereon, a driving motor provided with a driving wheel yieldingly maintained in engagement with said hand wheel and means for mounting said motor on said upright standard, said means comprising a stub shaft projecting into said head, and said motor being pivotally mounted to move about said shaft as an axis, said axis passing through substantially the center of gravity of said motor.

3. In combination, a sewing-machine head comprising an upright standard having a hand wheel mounted thereon, a driving motor provided with a driving wheel yieldingly maintained in engagement with said hand wheel, means for mounting said motor on said upright standard, said means comprising a stub shaft projecting into said

head, and said motor being pivotally mounted to move about said shaft as an axis, said axis passing substantially through the center of gravity of said dynamo-electric machine, and a spring so disposed as to bias said motor to move said driving wheel into engagement with said hand wheel.

4. In combination, a sewing-machine head comprising an upright standard having a hand wheel mounted thereon, a driving motor provided with a driving wheel yieldingly maintained in engagement with said hand wheel, means for mounting said motor on said head comprising a stub shaft projecting into said standard, said motor being pivotally mounted on said shaft, and a spring connected to said stub shaft and adapted to bias said motor to hold said driving wheel in engagement with said hand wheel.

5. In combination, a sewing-machine head comprising an upright standard having a hand wheel mounted thereon, a driving motor provided with a driving wheel yieldingly maintained in engagement with said hand wheel, means for mounting said motor on said upright standard comprising a stub shaft projecting into said standard, and a casing enclosing a portion of said shaft and pivotally mounted thereon, said casing being rigidly attached to said dynamo-electric machine.

6. In combination, a dynamo-electric machine provided with a casing, a pin projecting into one wall of said casing, and movable with respect thereto, and means engaging said pin for supporting said dynamo-electric machine, and a spring tending to rotate said pin with respect to said casing.

7. In combination, a dynamo-electric machine provided with a casing, a pin projecting into one wall of said casing, and movable with respect thereto, means disposed within said casing tending to rotate said pin with respect to said casing, and means engaging said pin for supporting said dynamo-electric machine.

8. In combination, a dynamo-electric machine provided with a casing, a pin projecting into one wall of said casing and movable with respect thereto, resilient means disposed within said casing tending to rotate said pin with respect to said casing, and means engaging said pin for supporting said dynamo-electric machine.

9. In combination, a dynamo-electric machine provided with a casing, a stub shaft projecting into one wall of said casing, a spring disposed within said casing and tending to rotate said shaft with respect to said casing, and means secured to the projecting end of said shaft for supporting said dynamo-electric machine.

10. In combination, a dynamo-electric machine provided with a casing, a stub shaft

projecting through said casing, a spring disposed within said casing and coiled about said shaft and tending to rotate the same with respect to said casing, the projecting portion of the stub shaft being provided with a threaded portion, and means for receiving the threaded portion of said shaft

for supporting said dynamo-electric machine.

In testimony whereof, I have hereunto ¹⁰ subscribed my name this fourth day of February, 1921.

LEWIS C. PACKER.
